UNITED STATES PATENT OFFICE

161,060

MOTOR VEHICLE OR SIMILAR ARTICLE

Jack J. Skelley, Butte, Mont.

Application September 8, 1950, Serial No. 12,112

Term of patent 14 years

(Cl. D14—3)

To all whom it may concern:

Be it known that I, Jack J. Skelley, a citizen of the United States of America, residing at Butte, in the county of Silver Bow and State of Montana, have invented a new, original, and ornamental Design for a Motor Vehicle or Similar Article, of which the following is a specification, reference being had to the accompanying drawing, forming a part thereof.

Figure 1 is a side perspective view of a motor vehicle or similar article, showing my new design.

The opposite side is similar to the side shown. The characteristic features of my design are shown in full lines in the drawings.

This application is a continuation-in-part of my pending application for Design Patent Serial No. D. 4,424, filed August 11, 1949.

I claim:

The ornamental design for a motor vehicle or similar article, as shown and described.

JACK J. SKELLEY.
